DESIGN FOR A BOTTLE FOR PERFUME OR THE LIKE

Norman Shapiro, New York, N. Y.

Application July 1, 1941, Serial No. 101,843

Term of patent 7 years

To all whom it may concern:

Be it known that I, Norman Shapiro, a citizen of the United States and a resident of New York city, county and State of New York, have invented a new, original, and ornamental Design for a Bottle for Perfume or the like, of which the following is a specification, reference being had to the accompanying drawing, forming part thereof.

Figure 1 is a perspective view of a bottle for perfume or the like showing my new design;

I claim:

The ornamental design for a bottle for perfume or the like, substantially as shown.

NORMAN SHAPIRO.
